UNITED STATES PATENT OFFICE

100,047

DESIGN FOR A SMOKING STAND

Edward Schultz, Chicago, Ill., assignor to The Nagel-Chase Mfg. Co., Chicago, Ill., a corporation of Illinois

Application January 18, 1936, Serial No. 60,645

Term of patent 14 years

To all whom it may concern:

Be it known that I, Edward Schultz, a citizen of the United States, residing at Chicago, in the County of Cook and State of Illinois, have invented a new, original, and ornamental Design for Smoking Stands, of which the following is a specification, reference being had to the accompanying drawing, forming a part thereof.

Figure 1 is a side elevation and Figure 2 is a horizontal section taken on line 2—2 of Fig. 1 of a smoking stand exhibiting my new design.

The design consists primarily of a cylindrical

body having a plurality of widely spaced ribs extending longitudinally thereof, the ribs having transversely concaved outer surfaces in contrast to the curvature of the body and relatively wide circumferential bands which adjoin the ends of the ribs and provide top and bottom portions of the body.

I claim:

The ornamental design for a smoking stand, as shown and described.

EDWARD SCHULTZ.
